RAIL JOINT

Walter Matlock, Baltimore, Md.

Application May 24, 1939, Serial No. 275,534

1 Claim. (Cl. 238—218)

This invention relates to rail joints and more particularly to means for taking up the expansion and contraction of the rails at the meeting ends thereof.

5 The object of the invention is to provide a rail joint of simple and efficient construction, the parts of which are so arranged as to compensate for the expansion and contraction of the rails due to climatic conditions and thus prevent 10 pounding of the car wheels at the junction of adjacent rails incident to the passage of a train thereover.

A further object of the invention is to provide 15 a rail joint comprising companion splice bars having registering slots formed therein and adapted to receive an insertible filler member formed of wood, rubber or other suitable material, said filler member serving to receive and absorb the impact of the rail securing bolts and prevent widening of the joint between adjacent rails.

A still further object of the invention is generally to improve this class of devices so as to increase their utility, durability and efficiency.

25 In the accompanying drawing forming a part of this specification and in which similar numerals of reference indicate corresponding parts in all the figures of the drawing:

Figure 1 is a side elevation of a rail joint showing the invention applied thereto,

30 Figure 2 is a horizontal sectional view taken on the line 2—2 of Figure 1,

Figure 3 is a transverse sectional view taken on the line 3—3 of Figure 1, and

35 Figure 4 is a detail vertical sectional view illustrating a modified form of the invention.

The improved device forming the subject-matter of the present invention is principally designed for application to the abutting ends of adjacent rails, and in Figure 1 of the drawing is shown in connection with a standard rail joint, in which 5 designates the cross ties, 6 and 7 the abutting ends of adjacent rails, 8 the splice bars and 9 the securing bolts. The upper edge of one of the splice bars 8 is formed with a sectional tread surface 10 which overlaps and bears against the adjacent rails 6 and 7 at the junction thereof so as to provide a smooth surface for the car wheels when a train is traveling on the track. The lower longitudinal edge of each splice bar is notched or recessed at 11 to accommodate the heads 12 of securing spikes 13 which latter are driven into the cross ties, as shown. The notches or recesses 11 in the splice bars 8, therefore, serve

to house the heads 12 of the spikes and prevent accidental withdrawal thereof. The securing bolts 9 pass through registering openings 14 in the splice bars and the webs 15 of the rails and the openings 14 on one or both sides of the abutting ends of the rails are preferably elongated longitudinally of the splice bars to form slots 16 adapted to receive removable filler keys or blocks 17. The filler blocks 17 may be formed of steel or wood, as illustrated in Figure 2 of the drawing, or of rubber or other yieldable material, as indicated at 18 in Figure 4 of the drawing. The outer faces of the filler blocks are convex to conform to the curvature of the outer walls of the slots 16 while the inner faces of the filler blocks are concave, as indicated at 19, and fit around and bear against the adjacent securing bolts 9. Interposed between the securing nuts 20 of the bolts 9 and the outer face of the adjacent splice bar on one or both sides of the abutting ends of rails are washers or retaining plates 21 which extend over the outer faces of the filler blocks 17 and serve to lock said filler blocks within the receiving slots 16.

Assuming the abutting ends of the rails are in 25 normal position, that is to say, at the limit of their expansive movement and due to climatic conditions, the rails tend to contract. This contraction of the rails would form a gap or opening between the abutting ends of the rails and thus cause pounding of the car wheels as they travel thereover. The filler blocks 17 prevent 30 this objectionable condition inasmuch as should the rails contract due to climatic conditions the securing bolts 9 will bear against said filler blocks and receive and absorb the impact incident thereto and prevent the formation of said gap and consequent pounding of the car wheels and this is particularly true when the filler blocks are 35 formed of rubber or other yieldable material. As the filler blocks 17 are removable, they can be readily replaced when necessary by merely removing the nuts 20 and retaining plates 21, as 40 45 will be readily understood.

A device constructed in accordance with the present invention will render riding on trains easier and more comfortable than heretofore inasmuch as there will be no objectionable pounding or hammering of the car wheels and vibration of the passenger coaches incident thereto as a train travels over the tracks.

It will, of course, be understood that the devices may be made in different sizes and shapes 50 55

and constructed from any suitable material without departing from the spirit of the invention.

Having thus described the invention, what is claimed as new is:

- 5 The combination with abutting rail sections including vertical webs having openings therein, of splice bars disposed on opposite sides of the rail sections and provided with transverse openings registering with the openings in the
- 10 rail webs, one of said splice bars being provided with an offset tread surface defining a horizontal shoulder, certain of the transverse openings in the splice bars being elongated longitudinally of the rail webs to form transversely alined slots
- 15 having oppositely disposed concave end walls, securing bolts extending through the openings in the rail webs and slots in the splice bars, removable concavo convex filler blocks of uniform

cross sectional diameter throughout their entire lengths and formed of resilient relatively compressible material fitting within the transversely alined slots and having their inner and outer ends flat with their inner ends bearing against the adjacent rail webs and with the convex portions thereof engaging the concave ends of the slots and with the concave portions bearing against the adjacent securing bolts, retaining plates mounted on certain of the securing bolts 10 and bearing against the outer flat ends of the adjacent filler blocks to prevent displacement thereof, the upper edges of the retaining plates fitting against the horizontal shoulder of the tread surface, and nuts engaging the bolts and 15 bearing against the outer faces of the retaining plates.

WALTER MATLOCK.
